ROCKET LAUNCHING APPARATUS

Fred C. Eastman, Marblehead, Mass., assignor to
 United Shoe Machinery Corporation, Flemington, N. J., a corporation of New Jersey

Application November 3, 1947, Serial No. 783,716

9 Claims. (Cl. 89—1.7)

1

This invention relates to a rocket launching apparatus particularly adapted for use in airplanes.

The invention has as its objective to facilitate the automatic indexing and firing of successive rockets from the apparatus as well as to improve the structure of the apparatus generally.

In accordance with one feature of the invention, therefore, the illustrated rocket launching apparatus, comprising a magazine with a firing tube and an exhaust tube at opposite ends thereof, means for indexing rocket carrying tubes into firing position in alignment with the firing tube, and means for firing the rocket, is provided with means for automatically initiating another indexing and firing cycle upon firing of each successive rocket.

In accordance with another feature of the invention, removal of defective or unfired rockets is facilitated by providing an ejecting or jettisoning station, which consists of an opening in the magazine normally closed by gates forming a continuous path for the rocket tubes in the magazine, and providing means for instituting a jettisoning cycle, during which the gates are released and the defective rocket moved from the firing station into position above the gates which open under the weight of the rocket so that it may drop through the opening.

These and other features of the invention will appear more fully from the following description when read in connection with the accompanying drawings and will be pointed out in the appended claims.

In the drawings,

Fig. 1 is a side view of the rocket launching apparatus;

Fig. 2 is a longitudinal sectional view through a rocket carrying tube showing a rocket mounted therein;

Fig. 3 is a front side, partly in section, of a portion of a rocket indexing mechanism and a driving mechanism therefor;

Fig. 4 is a sectional view of a clutch and brake associated with the driving mechanism;

Fig. 5 is an end view of a control mechanism for the clutch shown in its clutch-disengaging position;

Fig. 6 is a detail view of a portion of the clutch control mechanism;

2

Fig. 7 is an end view showing the structure of a lever and link assembly forming a portion of the control mechanism;

5 Figs. 8 and 9 are end views of the control mechanism in the positions assumed thereby during engagement of the clutch;

Fig. 10 is a side view, partly in section, of a mechanism for automatically initiating an indexing cycle, showing the parts in inoperative position;

10 Fig. 11 is an end view, partly in section, of the parts shown in Fig. 10.

Fig. 12 is a side view corresponding to Fig. 10, showing the parts in operative position;

15 Fig. 13 is a wiring diagram;

Fig. 14 is an angular view of a jettisoning mechanism; and

20 Fig. 15 is a view in end elevation of the rocket launching apparatus shown in Fig. 1, illustrating the rockets in the apparatus with a rocket and its tube in firing position and a rocket and its tube in loading position.

General

25 The illustrated rocket launching apparatus holds a plurality of rocket containing tubes which are successively brought into a firing position in the apparatus and fired therefrom. It is designed for use in airplanes and may conveniently be located either on the outside of the airplane below the bomb bay or within the bomb bay, in which latter case the lower portion of the apparatus projects through an opening in the airplane.

30 35 The apparatus consists of a magazine 10 (Fig. 1) provided with a firing tube 12 and an exhaust tube 14. The magazine comprises end walls or brackets 16, 18 and a body portion or sides 20 and has a noncircular, elongated shape. It is closed as well as sealed at all parts through

40 which flame leakage might occur to prevent the ignition of fumes within the airplane. An opening is provided at the top of the magazine through which access may be had to the interior of the magazine for the purpose of loading it with rockets. The opening is normally closed by means of a cover 22 pivoted to the brackets 16, 18. The cover may be locked in its closed position by latches 24 which engage pins 50 26 secured in the brackets 16, 18.

Illustrated in Fig. 2 is a tube 28 in which is contained a rocket 30. While the illustrated magazine is designed to hold six tubes, it can readily be expanded to hold a greater number of tubes by elongating the mid-section thereof heightwise.

Indexing

The tubes 28 with the rockets 30 are moved or indexed in the magazine in the following manner. Shafts 32, 34 (Figs. 1 and 3) are mounted to rotate in the brackets 16, 18. These shafts carry near their ends star wheels 36, 38 which engage successive rocket tubes 28 and feed them around the curved top and bottom portions of the magazine. The tubes are conveyed from the star wheels 36 to the star wheels 38 by guide rolls 40 carried by shafts 42 (only one shown in Fig. 1) which move with a portion of the drive mechanism, as will be described. The indexing of the tubes 28 is further facilitated by rolls 44 rotatably mounted in the ends of the star wheels 36, 38, the rolls 44 tending to roll the tubes 28 along the inner face of the magazine body 20.

The shafts 32, 34 are rotated by a motor 46 (Fig. 3) through a clutch and a variable speed mechanism. The motor 46 is secured to a housing 48 which contains the variable speed drive parts and is attached to the bracket 18. A motor gear 50 (Fig. 3), rotated by the motor, meshes with a gear 52 (Figs. 3 and 4) forming the driving part of a multiple disk clutch 54 of conventional type. The clutch disks are mounted on a shaft 56. The clutch 54 is engaged and a multiple disk brake 60 of conventional type is disengaged by a spring 58 (Fig. 4) which moves a clutch controlling operating screw 62 and a shaft 64 connected to the screw lengthwise (to the right of Fig. 4). Reverse movement of the screw 62 and the shaft 64 disengages the clutch and engages the brake.

When the clutch 54 is engaged to rotate the shaft 56, a pinion 66 secured to the shaft 56 rotates an intermediate reduction gear 68 mounted in bearings 70 in the housing 48. A pinion 72 integral with the said gear 68 meshes with a gear 74 on a shaft 76 which is also mounted to rotate in the housing 48 and may be designated as the input shaft into a variable speed drive 78. The variable speed drive 78 is a combination of a continuous motion with a differential and produces a harmonic or intermittent movement. Thus the input shaft 76 of the variable speed drive is rotated at substantially constant velocity, but an output shaft 80 of said drive 78 will move at varying velocity so that at the beginning and the end of each cycle the velocity of the shaft 80 is zero and its acceleration is zero or substantially zero. The velocity of the shaft 80 accordingly is gradually increased at the beginning of each cycle and gradually decreased at the end of each cycle, making a smooth operation of the indexing mechanism at high speeds possible. Such variable speed drives are well known and are described, for example, in United States Letters Patent No. 2,309,595, granted January 26, 1943, upon application of Lester E. James.

The output shaft 80 of the variable speed drive, which shaft is also a sprocket shaft, carries a sprocket 82. Rotation of the sprocket 82 is transmitted to a sprocket 84 on a shaft 86, mounted to rotate in the bracket 18, by means of a chain 88. Pinions 90, 92 likewise secured to the shafts 80, 86 mesh with gears 94, 96 on shafts 98, 100 rotatably mounted in the bracket 18. Pinions 102, 104 on the shafts 98, 100 mesh with pinions

106, 108 on the aforementioned shafts 32, 34. Only the series of gears and pinions at the right side of the magazine 10 is illustrated in Fig. 3. A corresponding series of drive parts comprising pinions, gears, sprockets, and a chain is provided at the left side of the magazine, rotation being imparted to the drive parts at the left side by the shaft 80 through the drive parts at the right side of the magazine and through the shafts 32, 34. The chains 88 carry the aforementioned shafts 42 so that the rolls 40 move with the chains.

Indexing control

15 As previously mentioned, engagement and disengagement of the clutch 54 and the brake 60 are effected upon lengthwise movement of the screw 62. Movement of the screw 62 is controlled by an adjustable screw 110 (Figs. 3, 4, 5, and 6) mounted in a lever 112 and held in adjusted position by a nut 114 (Fig. 6). The lever 112 is secured to a shaft 116 which rotates in bearings in a bracket 118 secured to the aforementioned housing 48. Likewise joined to the shaft 116 is a lever 120 to which is pivotally connected a rod 122.

The screw 110 is normally held in its inner, clutch disengaging position by a pair of complementary, curved levers 124, 126 (Fig. 5). The upper end of the lever 124 is pivoted at 128 to the rod 122 and its lower end is pivoted at 130 to a pair of links 132, the outer of which is shown in Fig. 5 and the inner of which is shown in Fig. 7. The links 132 are pivotally joined at 134 to the upper end of the lever 126. The lower end of the lever 126, in turn, is pivoted at 136 to a two-armed lever 138 which, between its ends, is mounted to swing about a pin 140 secured in the housing 48. With the pivots 128, 130, 134, 136 in alignment the levers 124, 126 have the effect of a straightened toggle, locking the screw 110 in its clutch disengaging position.

To swing the levers 124, 126 to shift the pivot pins 130, 134 and break the toggle effect of the levers, a latch 142 (Figs. 5 and 7) is provided. 45 The latch 142 is mounted to rotate about a fulcrum pin 144 secured in the housing 48 and is connected to the lever 126 by two clutch release links 146, one of which is shown in Fig. 5 and the other of which is shown in Fig. 7. The links 50 146 are joined to the latch 142 by a pivot pin 148 and to the lever 126 by the pivot pin 136. Guide links 150, the left ends (Fig. 5) of which are mounted on the fulcrum pin 144, carry at their right ends a roll 152 arranged between the inner curved faces of the levers 124, 126 and about which the levers 124, 126 may roll when they are shifted by movement of the latch 142. A pivot pin joining the roll 152 to the links 150 extends through the central portions of the links 55 132.

A pawl 154 is provided to swing the latch 142 clockwise (Figs. 5 and 7) against the action of a spring 156 to break the toggle effect of the levers 124, 126 and permit the spring 58 to effect engagement of the clutch 54. The pawl 154 is pivoted to the bifurcated arm of a lever 158 (Fig. 5) which swings about a fixed fulcrum pin 160 in the housing 48. A leaf spring 162 which is secured to the lever 158 by an adjustable screw 164 normally holds the pawl 154 in engagement with the latch 142.

The pawl 154 may swing relatively to the lever 158 until an abutment 166 on the pawl 154 engages the screw 164. Thereafter the pawl 70 moves as a unit with its lever 158 about the ful-

crum pin 160, as will be described more in detail below. Movement is imparted to the pawl 154 by a solenoid 168. The solenoid 168 is carried by a solenoid bracket 170 secured to the housing 48 and is joined to the pawl 154 by a connection 172.

Operation of indexing control

When the solenoid 168 is energized, the pawl 154 is swung counterclockwise (Fig. 5) about its connection with the lever 158 until the abutment 166 engages the screw 164 (Fig. 8). This movement of the pawl 154 swings the latch 142 clockwise (Fig. 5) about its fulcrum pin 144, against the action of the spring 156. Clockwise movement of the latch 142 shifts the links 146 horizontally. Since the pivot pin 136 at this time is fixed by engagement of the high face of a cam 176 with a roll 174 carried by the right-hand end of the lever 138, the links 146 move the pivot pins 130, 134 in a clockwise path about the roll 152, whereby the pivot pins 130, 134 are moved out of alignment with the pins 128, 136, as shown in Fig. 8, and the levers 124, 126 are displaced, disturbing their toggle or locking effect, as may be determined by comparison of Figs. 5 and 8. This displacement of the pivot pins 134, 130 and the corresponding movement of the levers 124, 126 permit the spring 58 (Fig. 4) to move the screws 62, 110 outward, the lever 112 moving outward about the shaft 116 with the screw 110 and the rod 122 moving upward (Fig. 8). The spring 58 in thus shifting the screw 62 to the right of Fig. 4 engages the clutch 54 and disengages the brake 60, whereupon the motor 46 rotates the shaft 56 and, through the gears and pinions 66, 68, 72, 74, 90, 92, 102, 104, rotates the shafts 32, 34, thus effecting an indexing cycle and moving a tube 28 into firing position in the magazine 10.

As the cam 176, which is secured to the outer end of the input shaft 76 rotates counterclockwise (as seen in Fig. 5) with the shaft 76, the roll 174 moves onto the low face of the cam 176, permitting the corresponding end of the lever 138 to move downward and the other lever end, which is joined to the lever 126 by the pivot pin 136, to move upward. The pivot pin 128 has become fixed by the outward movement of the screw 110 and the upward movement of the rod 122 so that the upward movement of the pivot pin 136 with the left-hand end of the lever 138 tends to shift the links 146, 150 into the inclined position shown in Fig. 9, thereby moving the floating assembly, comprising the levers 124, 126 and the links 132, into a higher position. Moreover, after engagement of the abutment 166 on the pawl 154 with the screw 164, the pawl and its lever 158 were moved as a unit clockwise (Fig. 9) about the pin 160, during continued upward movement of the solenoid connection 172, and the pawl 154 swung outward out of engagement with the latch 142, as shown in dash lines in Fig. 9, permitting the spring 156 to swing the latch 142 counterclockwise (Fig. 9) about its fulcrum pin 144 and to bring the pivot pins 128, 130, 134, 136 into alignment again.

The parts are restored to their original positions as follows. When the solenoid is deenergized, the lever 158 and the pawl 154 move downward and the spring 162 swings the pawl back into locking engagement with the latch 142. As the shaft 76 completes its rotary movement, the high face of the cam 176 again engages the roll 174 swinging the lever 138 counterclockwise (Fig. 9) about the pin 140. This effects a downward move-

ment of the left end of the lever 138, moving the lever assembly 124, 126 downward as a unit and returning the links 132 to their normal vertical positions. This downward movement of the levers 124, 126 swings the screw 110 inward or to the left of Fig. 4 through the rod 122 and the lever 112. Inward movement of the screw 110 shifts the screw 62 to the left of Fig. 4, against the pressure of the spring 58, disengaging the clutch and engaging the brake. The clutch now is locked in disengaged position again by the levers 124, 126.

Automatic firing control

As has been stated before, it is the purpose of the present invention to be able continuously to fire successive rockets as they are automatically indexed into firing position. Before describing the electrical system which makes this possible, a switch control instrumental in effecting the desired purpose will be described.

Secured to the firing tube 12 outside of the magazine 10 is a casing 178 (Figs. 10, 11, and 12) containing two gas-tight chambers 180, 182 (Fig. 11) separated from each other by an inner wall 184. Mounted to rotate in the wall 184 and extending into both chambers is a shaft 186. The shaft end extending into the chamber 180 carries a lever 188 (Fig. 10), the end of which extends downward through a hole 190 in the firing tube and is positioned in the path of the rocket as it passes through the firing tube.

Secured to the shaft 186 within the chamber 182 is a cam 192. A spring 194 tends to hold the cam 192 in its inoperative position and the end of the lever 188 in its downward position, extending into the firing tube. One end of the spring is joined to the cam 192 and the other end is joined to a bifurcated member comprising a bolt 196 and a clamp 198, each provided with a prong, said member maintaining the spring under preliminary tension. As the fired rocket passes through the tube 12, the force of the rocket swings the lever 188 upward into the position shown in dotted lines in Fig. 12, in which position the lever 188 engages a stop 200. Upward movement of the lever 188 rotates the shaft 186 and the cam 192 simultaneously, further tensioning the spring 194. In rotating, the high face of the cam 192 is brought into engagement with a switch 202 which, as will be described below, closes the circuit of the indexing solenoid 168 (Fig. 5). The spring 194 returns the cam 192 and the lever 188 to their initial positions after the rocket has passed the hole 190.

Indexing and firing systems

In describing an automatic rocket firing cycle, it will be assumed that a rocket has been indexed to firing position in the magazine 10 (Fig. 1) in which position a ground contact ring 204 (Fig. 2) on the rocket tube 28 is in engagement with a grounded plunger 206 in the magazine 10. A positive contact ring 208 on the tube 28 engages a terminal 210 in the magazine. As likewise shown in Fig. 2, wires 212, 214 leading from the rocket are attached to ground and positive terminals 216, 218 on the inner face of the tube 28 which terminals are connected, respectively, to the contact rings 204, 208. The power is turned on to start the motor 46 (Fig. 13) by closing a motor switch 220 on a switchboard B. This establishes a circuit from the positive side of the source of power through a motor relay 228 to ground, causing the armature of the relay to be drawn up to connect the positive side of the

source of power to a wire 229 which is also permanently connected to the armatures of four other relays, to be referred to hereinafter, and to one terminal of the motor 46, the other terminal of which is grounded. A switch 222, which may be termed a timing switch, in the firing circuit is held closed by the lever 138 when the roll 174 is upon the high face of the cam 176 (Fig. 5).

Closing of an "automatic firing" switch 224 (Fig. 13) to fire the rocket located in firing position establishes a circuit through a relay coil 226, namely: from the positive side of the source of power through the motor switch 220, the automatic firing switch 224, and the relay 226 to ground, drawing up its armature. Thus a circuit is established from the positive wire 229 through the armature of the relay 226, a line 230, the switch 222, the terminal 210, the squib of the rocket, and the plunger 206 to ground.

Firing of the rocket by closing of the firing circuit, as described in the preceding paragraph, causes the switch 202 to be closed by upward movement of the lever 138 (Fig. 12) and rotation of the cam 192 and an indexing circuit is then completed as follows: from the positive side of the source of power through the armature of the relay 228, the line 229, the armature of the relay 226, a line 232, the switch 202, a line 234, and the solenoid 168 to ground. During the indexing, the timing switch will be opened but upon completion of the indexing cycle, the timing switch 222 will again be closed by the cam 176 and the next firing cycle will automatically be initiated, the firing circuit being completed in the manner aforescribed, as long as the switch 224 is held closed.

If desired, each rocket, as has heretofore been customary, may be fired individually, at any time desired, in the following manner. With the motor circuit closed, a "single firing" switch 236 is closed. This establishes the following circuits to fire a rocket, namely: (a) from the positive side of the source of power to the motor switch 220, the single firing switch 236, a relay 238, whereby the armature of the relay 238 is drawn up, to ground, and (b) from the positive side of the source of power, to the armature of the relay 228, the armature of the relay 238, the line 230, the switch 222, the terminal 210, the squib of the rocket, and the plunger 206 to ground.

After firing the rocket in this manner, it is then necessary to bring about an indexing cycle to move another rocket into firing position. To do so, an indexing switch 240 is closed, establishing the following circuits: (a) from the positive side of the source of power to the motor switch 220, the indexing switch 240, a relay 242, and ground, whereby the armature of said relay is drawn up, and (b) from the positive side of the source of power to the armature of the relay 228, the armature of the relay 242, a line 244, and the solenoid 168 to ground.

When the magazine is to be loaded, the cover 22 (Fig. 1) is opened and the motor circuit is closed by a switch 246 (Fig. 13) located more conveniently relatively to the magazine than is the switchboard containing the automatic firing, single firing, and other switches previously mentioned. With the motor circuit closed, closing a loading switch 248 establishes the following circuits: (a) from the positive side of the source of power, through the switch 246, the switch 248, and the relay 242 to ground, and (b) from the positive side of the source of power to the armature of the relay 228, the armature of the relay

242, the line 244, and the solenoid 168 to ground, thus initiating an indexing cycle.

Jettisoning

At times a dud or misfire is encountered and it is necessary to remove the defective rocket from the magazine before firing can be continued. Such a rocket is removed by jettisoning in the following manner. Immediately beyond the firing position (in the direction of indexing) the magazine is provided with an opening the width and length of which correspond to that of a tube 28. The guideway or path of the rocket across this opening during normal indexing of the rocket is formed by a pair of gates 250 (of which only one is shown in Fig. 14). Since the gates and their release mechanism are identical at both ends of the opening, only one has been illustrated in Fig. 14 and only one will be described. Each gate 250 is pivoted at 252 to the magazine and the gates are swung together into an indexing path-forming position in engagement with stop faces 254 on the magazine by torsion springs 256, of which only one is shown. The springs 256 are mounted on the pivots 252, one end of each spring engaging a pin 258 secured to the corresponding gate 250. The gates are locked in closed position by a latch 260 which engages the adjacent gate faces, as illustrated. The latch 260 is pivotally mounted at 262 in lugs on the magazine 10 and is also pivoted to a link 264. The link 264 in turn is pivotally joined to a two-armed lever 266. The lever 266 is mounted between its ends to swing about a pin 268 mounted in lugs in the magazine 10. A connection 270 joins the lever 266 to a jettison solenoid 272.

When the solenoid is energized, as will be described below, the lever 266 is swung clockwise about the pin 268 (Fig. 14), shifting the link 264 to the left and moving the latch 260 out of engagement with the gates 250. As the rocket and its tube are then moved beyond the firing station and into position over the gates 250 by closing the indexing circuit, said gates will be opened by the weight of the rocket and permit the rocket and its tube to drop out of the magazine. If the magazine is located within the bomb bay, the opening in the magazine will be positioned directly above a corresponding opening in the bomb bay. A pin 274 moved inward into the magazine, by clockwise movement of the lever 266 about the pin 268, prevents the rocket from accidentally rolling beyond the magazine opening and into the magazine. When the rocket has dropped out of the magazine, the springs 256 return the gates to their closed position. Deenergizing the solenoid causes the gate release parts to return to their initial position, the latch 260 again locking the gates 250.

In order that the rocket may be jettisoned by movement beyond the firing position and over the opening in the magazine, an indexing cycle must be initiated as indicated above. The jettison solenoid 272 is arranged in the circuit of the indexing solenoid 168 so that closing of a jettison switch 276 (Fig. 13) will simultaneously effect an indexing cycle of the rockets and an energizing of the solenoid 272. Assuming that the motor circuit is closed, closing the jettison switch 276 establishes a circuit through a relay coil 278 and the jettisoning-indexing circuit is completed as follows: from the positive side of the source of power, through the armature of the relay 228, the armature of the relay 278, and the jettison solenoid 272 to ground; and simultaneously from

the positive side of the source of power, through the armature of the relay 228, the armature of the relay 278, the line 244, and the solenoid 168 to ground. Upon completion of the indexing cycle initiated by closing the jettison switch 276, another rocket has been moved into firing position and the regular firing cycles, either single or automatic, can then be resumed.

Operation

The launching apparatus is operated in the following manner. It is assumed that the magazine is loaded and that a rocket is stationed in the firing position. The firing switch is closed and the rocket is fired. If the single firing switch 236 (Fig. 13) is used, the indexing switch 240 must then be pressed to initiate the indexing cycle and move the next rocket into firing position. If the automatic firing switch 224 has been closed, firing of the rocket will have swung the lever 188 upward so that the cam 192 has closed the switch 202. In either case, the solenoid 168 (Fig. 5) is energized to swing the pawl 154, thus rotating the latch 142. The latch 142 displaces the levers 124, 126 through the links 146, permitting the spring 58 (Fig. 4) thereupon to move the screws 62, 110 outward and to engage the clutch 54 and disengage the brake 60. Engagement of the clutch 54 permits the motor 46 to rotate the shaft 56 and, through the gears 68, 72, 74, the variable speed drive 78 (Fig. 3), and the pinions and gears 90, 92, 94, 96, 102, 104, 106, 108, to rotate the shafts 32, 34. Rotation of said shafts causes the star wheels 36, 38 to index the rockets, moving another rocket into the firing position. Substantially at the end of the indexing movement, the cam 176, which is rotated with the variable speed drive 78, swings the lever 138 (Fig. 5) and thereby (a) returns the screw 110 to its inward position through the levers 124, 126 and the rod 122, and (b) closes the timing switch 222 in the firing circuit. Inward movement of the screw 110 shifts the screw 62 to the left of Fig. 4, engaging the brake 60 and disengaging the clutch 54. Since the levers 124, 126 and the links 146 have been returned to their initial positions, the screw 110 is held locked in its clutch disengaging position. If the automatic firing switch is closed, the next firing cycle will automatically be instituted by the closing of the switch 222. If the single firing switch is used, closing the switch 236 will effect firing of the next rocket. After each rocket is fired its tube is moved out of firing position during the succeeding indexing operation. The empty tubes are indexed in the magazine until they are removed for reloading.

Whenever a dud or misfire is encountered, the jettison switch 276 is closed, effecting an indexing cycle and releasing the gates 250 (Fig. 14). The defective rocket, in moving out of firing position and into position over the gates 250, causes the gates to open under the weight of the rocket and the rocket will then fall through the opening. The springs 256 immediately return the gates to their closed positions and the jettisoning solenoid is deenergized, permitting the latches 260 to return to gate-locking position. Firing may then be resumed by closing either of the firing switches.

Having thus described my invention, what I claim as new and desire to secure by Letters Patent of the United States is:

1. In a rocket launching apparatus including a firing tube and a magazine for a plurality of rocket

carrying tubes, the combination with means for indexing the rocket carrying tubes in the magazine from a loading position to a firing position in register with the firing tube, and means for firing a rocket from the firing position, of means rendered operative by the rocket passing through the firing tube upon firing to effect automatic indexing and firing of a succeeding rocket.

2. In a rocket launching apparatus including a firing tube and a magazine for a plurality of rocket carrying tubes, means for indexing the rocket carrying tubes in the magazine from a loading position to a firing position in register with the firing tube, means including an electric firing circuit for firing a rocket located in firing position, means rendered operative by the fired rocket passing through the firing tube automatically to actuate the indexing means to move another rocket into firing position, and means in said firing circuit rendered operative by the indexing mechanism at the conclusion of the indexing cycle automatically to fire the rocket moved into firing position.
3. In a rocket launching apparatus having a magazine for a plurality of rocket carrying tubes and a firing tube, the combination with operator-controlled means for indexing the rocket carrying tubes successively from a loading position to a firing position in register with the firing tube and firing means for firing the rockets one at a time, of means rendered operative after the firing of the first rocket to effect automatic and continuous indexing and firing of the remaining rockets by the passage of each rocket through the firing tube, said last-named means comprising an automatic firing switch that is closed to fire the first rocket, a housing secured to the firing tube, a lever secured to a shaft in the housing and projecting into the path of travel of a rocket through the firing tube, a cam on the lever shaft, and an indexing switch in the housing, said switch being closed by the cam to initiate an indexing cycle each time the lever is actuated by the rockets passing successively through the firing tube.
4. In a rocket launching apparatus including a firing tube and a magazine for a plurality of rocket carrying tubes, means for indexing the rocket carrying tubes in the magazine from a loading position to a firing position in register with the firing tube, an electric circuit associated with the indexing means, an electric circuit for controlling the firing of a rocket from the firing position, both electric circuits being supplied from a common source of power, a firing switch, and interlocking switches cooperating with the firing switch to effect continuous indexing and firing of successive rounds from the apparatus.
5. In a rocket launching apparatus including a firing tube and a magazine for a plurality of rocket carrying tubes, means for indexing the rocket carrying tubes in the magazine from a loading position to a firing position in register with the firing tube, a motor for actuating the indexing means, a clutch for transmitting the output of the motor to the indexing means, means including a firing circuit for firing the rocket from the firing position, an electric indexing circuit, a solenoid in the indexing circuit, means rendered operative by the fired rocket passing through the firing tube to energize the solenoid, clutch controlling means moved by the solenoid from a position in which said clutch is held disengaged to a position in which the clutch becomes engaged, means activated by the indexing means at the end of the indexing cycle to shift said clutch

controlling means into the position in which the clutch is disengaged, and means rendered operative by the last-named means automatically to fire the round moved into firing position by the indexing means.

6. In a rocket launching apparatus including a firing tube and a magazine for a plurality of rocket carrying tubes, means for indexing the rocket carrying tubes in the magazine from a loading position to a firing position in register with the firing tube, a clutch associated with the indexing means, means including an electric firing circuit for firing a rocket indexed into firing position, an electric indexing circuit, a solenoid arranged in the indexing circuit, a rotatable lever extending into the firing tube and swung by the fired rocket passing through the firing tube, a solenoid controlling cam movable with said lever, a switch in the indexing circuit closed by the movement of the solenoid controlling cam to energize said solenoid, a lever mechanism for controlling said clutch and operated upon energizing of the solenoid to effect engagement of the clutch, a firing controlling cam rotated by the indexing mechanism, a rotatable lever moved by said firing controlling cam upon conclusion of the indexing cycle to operate said lever mechanism to disengage the aforementioned clutch, and a switch in the firing circuit closed by the firing controlling cam to initiate another firing cycle.

7. In a rocket launching apparatus including a firing tube and a magazine for a plurality of rocket carrying tubes, the combination with means for indexing the rocket carrying tubes in the magazine from a loading position to a firing position in register with the firing tube, an electric circuit associated with the indexing means, an electric circuit for controlling the firing of a rocket, a firing switch for closing the firing circuit to effect firing of the rocket, and an indexing switch for closing the indexing circuit to effect an indexing cycle, of another firing switch and interlocking switches cooperating therewith to effect continuous indexing and firing of successive rounds.

8. In a rocket launching apparatus including a

firing tube and a magazine in which a plurality of rocket carrying tubes are moved along an indexing path to index successive rockets into firing position in register with the firing tube, means for firing

- 5 a rocket located in the firing position, movable gates normally held in locked position to provide a guideway for the rockets during indexing across an opening in the magazine adjacent to the firing position, and means for releasing the gates and 10 instituting an indexing cycle when the rocket located in firing position is undischarged, whereby the undischarged rocket is moved over said released gates to drop from the magazine and another rocket is moved into firing position.
- 15 9. In a rocket launching apparatus including a firing tube and a magazine in which a plurality of rocket carrying tubes are moved along an indexing path to index successive rockets into firing position in register with the firing tube, movable 20 gates normally held in closed position to provide a guideway for the rockets during indexing across an opening in the magazine adjacent to the firing position, movable latches for locking the gates in closed position, rotatable levers for moving the 25 latches, solenoids for rotating the levers, when energized, to move the latches out of gate-locking position, means for energizing the solenoids and for instituting an indexing cycle when the rocket located in firing position is undischarged, 30 whereby the undischarged rocket is moved over the released gates to drop through the opening in the magazine, means moved into operative position by said rotatable levers upon energizing of the solenoids to prevent the rocket from moving 35 along the indexing path beyond the gates, and means for returning the gates to closed position.
